DESIGN FOR A COMBINED HEAT AND SUN LAMP

Frederic C. Winkler and David T. Beggs, Cleveland, Ohio, assignors to Westinghouse Electric Corporation, a corporation of Pennsylvania

Application November 1, 1945, Serial No. 123,378

Term of patent 14 years

(Cl. D48—20)

To all whom it may concern:

Be it known that we, Frederic C. Winkler and David T. Beggs, citizens of the United States, residing at Cleveland, in the county of Cuyahoga and State of Ohio, have invented a new, original, and ornamental Design for Combined Heat and Sun Lamp, of which the following is a specification, reference being had to the accompanying drawing, forming a part thereof, in which:

Figure 1 is a perspective view of a combined heat and sun lamp embodying our new design;

Fig. 2 is a front or back elevational view thereof; and

Fig. 3 is a side elevational view thereof.

The dominant features of our design reside in the portions shown in full lines in the drawing.

We claim:

The ornamental design for a combined heat and sun lamp, as shown and described.

FREDERIC C. WINKLER.
DAVID T. BEGGS.
